UNITED STATES PATENT OFFICE.

EDGAR E. BROSIUS, OF PITTSBURGH, PENNSYLVANIA.

MUD GUN.

Application filed August 4, 1926. Serial No. 127,000.

The present invention relates to mud guns of the character utilized for stopping the tapping holes or iron notches of blast furnaces at the completion of each furnace casting operation.

At the present time it is customary in the art to which the present invention relates to utilize artificial means in many cases for the plugging of tapping holes after a furnace casting operation. It is desirable that guns for this purpose shall have a capacity such that recharging thereof during a plugging operation is not necessary so that a plugging operation once started may be quickly completed.

It is further desirable that mud guns for the purpose referred to shall be effective during the plugging operation for preventing possibility of the furnace blowing out wardly through the mud gun barrel. In this connection, it is of importance, from a practical standpoint, to be able to maintain full pressure within a blast furnace without fear of any possibility of damage by reason of such a blowing out operation. The present invention has for one of its objects the provision of an improved mud gun having such a capacity that complete plugging of a tapping hole may be expeditiously obtained without any reloading or manual addition of clay to the gun during such closing operation.

Another object of the present invention is to provide a mud gun of the character referred to effective for continuously exerting a sufficient pressure on previously discharged clay to prevent any possibility of a blowing back of such clay by reason of the blast furnace pressure.

A still further object of the present invention is to provide a mud gun of comparatively large capacity so constructed that not only is the provision of a separately operable valve rendered unnecessary for controlling the discharge of clay, but of such nature that the operating parts are so disposed as not to be subjected to any undue heat from the furnace, and so arranged that an extremely compact, well balanced and easily refilled structure is afforded.

In the accompanying drawings, I have shown for purposes of illustration only, certain preferred embodiments of my invention, it being understood that the drawings do not define the limits of my invention as changes in the construction, relative ar-

rangement and operation of the parts may be made without departing either from the spirit of the present invention or the scope of my broader claims. In the drawings, 60

Figure 1 is a top plan view of one form of mud gun constructed in accordance with the present invention;

Figure 2 is a longitudinal vertical sectional view on the line II—II of Figure 1; 65

Figure 3 is a vertical transverse sectional view on the line III—III of Figure 2;

Figure 4 is a transverse, sectional view on the line IV—IV of Figure 2 looking in the direction of the arrows; 70

Figure 5 is a transverse sectional view on the line V—V of Figure 2 looking in the direction of the arrows;

Figure 6 is a view similar to Figure 1, illustrating a modified embodiment of the 75 invention,

Figure 7 is a vertical sectional view on the line VII—VII of Figure 6, certain of the supporting and clamping parts being shown in elevation, and 80

Figure 8 is a vertical transverse sectional view on the line VIII—VIII of Figure 7, certain of the clamping bolts being shown in elevation.

In my prior United States Patent No. 85 1,288,496 of December 24, 1918 there is disclosed a mud gun adapted for the general use herein contemplated and comprising a reservoir adapted to automatically feed the gun chamber during the plugging operation. 90

In the construction shown in that patent, the reservoir is illustrated as being arranged with its axis substantially normal to the axis of the gun chamber and as having a valve communication with the gun chamber. 95

In many cases I have found that it is desirable to effect a feeding from the reservoir to the gun chamber without the use of separate valve means. I have also found that in many instances, by reason of limitations 100 of space and the like, it is desirable to dispense entirely with vertically mounted reservoir means. The construction herein disclosed may, in connection with the features of operation set forth, be considered as constituting an improvement over the structure disclosed in said patent.

Referring more particularly to Figures 1 to 5, both inclusive, of the drawings, there is illustrated a plugging apparatus comprising 110 a gun chamber 2 provided with a discharge nozzle or outlet 3. Clay within the

gun chamber 2 is adapted to be discharged therefrom by the operation of the piston 4 carried by a piston rod 4^a actuated by the piston 5 in the fluid pressure actuating cylinder 6. These parts, with respect to their general characteristics, may be of any standard construction. Disposed intermediate the gun chamber 2 and the fluid pressure actuating cylinder is shock absorbing means 7 10 preferably in the form of a coil spring surrounding the piston rod 4 whereby the movement of the piston in a rearward direction may be checked or cushioned gradually.

Mounted above the gun chamber and fluid pressure actuating cylinder is a reservoir 8 adapted to discharge its contents into the gun chamber 2 by reason of the elbow connection 9, the elbow connection communicating with an inlet opening 10 into the gun chamber adjacent the limit of travel of the piston 3 therein and so located that with the piston at the extreme end of its forward travel as illustrated in Figure 2 of the drawings the piston will be effective for completely closing this opening.

Mounted for operation within the reservoir 8 is a piston 11 carried by a piston rod 12 on the opposite end of which is mounted an actuating piston 13 travelling within the fluid pressure cylinder 14. Intermediate the reservoir 8 and the fluid pressure cylinder 14 there is preferably provided cushioning means 15 for the piston 11, similar to the cushioning means 7 heretofore described.

35 In the embodiment illustrated in these figures of the drawings, the two sets of cylinders are illustrated as having substantially parallel axes and as being directly superimposed. By reason of this construction, an 40 extremely compact gun structure is provided, making it possible to utilize a reservoir 8 of relatively great length and of a diameter determined with reference to available fluid pressure supplies and capacity required. At the same time, the operating cylinders for both the gun chamber and the reservoir are necessarily disposed at a considerable distance from the furnace whereby they are not subjected to extreme temperatures. The entire apparatus in use is adapted to be suspended from a central bracket 16 within which may travel a pin or roller 17. Adjacent the front end of the gun the elbow connection 9 is formed with enlarged 50 bosses 18 from which project trunnions 19 adapted to cooperate with arms carried by a clamp shaft as well understood in the art. By my construction, however, the clamp arms are spaced apart on the clamp shaft. This is a distinct advantage in that there is less likelihood of their becoming fouled on cinder skulls which may build up on the trough. Furthermore, the lugs 60 18, on the elbow connection 9, are in such positions that the clamp shaft may be

raised higher than is ordinarily permissible. Increased elevation of the clamp shaft is desirable inasmuch as it avoids warping or bending of the shaft.

For permitting the gun chamber and the reservoir to be filled with clay prior to the commencement of a plugging operation, they are each provided with a laterally arranged charging opening 20. These openings are located as indicated more particularly in Figures 4 and 5 of the drawings and after the desired amount of clay has been charged through them they may be closed in any suitable manner as by closure plates 21.

In operation, with a construction of the character described, a cap will be placed over the discharge outlet 3 and the gun chamber 2 completely filled with clay. Thereafter, the reservoir 8 will be filled through its opening 20. When both the gun chamber and the reservoir are filled, the gun is ready for use and may be moved into position preparatory to the plugging operation, the cap being at this time removed from the discharge outlet. Fluid under pressure will be admitted to the outer end of the cylinder 6 for the purpose of moving the piston 5 to the right as viewed in Figure 2, this movement being effective through the piston 3 for completely emptying the gun chamber. Thereafter, fluid will be admitted to the opposite end of the cylinder 6 for retracting the piston 5 the desired amount and fluid pressure will be applied to the left hand end of the cylinder 14, the fluid pressure being sufficient to tend to constantly urge the clay in the reservoir 8 to move through the elbow connection 9 into the gun chamber. After the desired amount of clay has been forced from the reservoir into the gun chamber, fluid pressure will again be admitted to the left hand end of the cylinder 6 and such additional amount of clay plugged into the tapping hole. As the piston 4 completes its forward travel, it will be effective for sealing the opening 10 to prevent the further inflow of clay until the piston 4 is again retracted. During the entire operation of the apparatus, the furnace is prevented from blowing out through the mud gun by reason of the resistance of the piston 4 and also the resistance afforded by the pressure in back of the piston 13.

In normal operation, it is customary after having ejected the original contents from the gun chamber to only impart a short stroke to the piston 5, such stroke being imparted comparatively quickly whereby a succession of hammer blows is given to the fresh charges of clay forced into position through the opening 10. The manner of operation of the apparatus may be varied as desired.

The elbow connection 9 may be provided with a pivotally mounted closure 22 by

means of which access may be had to the interior of the connection for cleaning out purposes or the like.

In Figures 6, 7 and 8, there is illustrated a construction similar to that already described, but differing therefrom in that twin reservoirs are provided in place of the single reservoir before referred to. Parts corresponding to the parts already described are designated by the same reference characters having a prime affixed thereto. In this modified arrangement, a balanced structure may be obtained by having the reservoirs 8' and their actuating cylinders 14' symmetrically located on opposite sides of the longitudinal axis of the gun chamber 2' and its actuating fluid pressure cylinder 6'. This makes it possible to locate the charging opening 20' for the gun chamber directly in the top thereof, and close the same by a pivotally mounted closure 21' held in position by a latch 23 mounted to be oscillated about the axis 24.

Each of the reservoirs 8' likewise has a charging opening directly in the top thereof of normally closed by pivotally mounted closure 21' suitably held in position.

The two reservoirs 8' discharge into the gun chamber through a common opening 10', this opening being accessible for cleaning out purposes or the like through removal of the closure 22'.

In both forms of my invention it will be apparent that the piston movable within the gun chamber is effective during its reciprocations for not only ejecting clay from the gun chamber but for controlling the delivery of additional clay thereto from the reservoir or reservoirs provided for that purpose. This makes it unnecessary to provide any supplemental valve for controlling this communication and makes the amount of clay delivered exactly proportional to the stroke of the piston rod 4 or 4'. This constitutes one advantage of the present invention.

Another advantage of the invention arises from the provision of a gun chamber having one or more reservoirs communicating therewith through an opening controlled by the gun itself independently of any valves, and particularly where the reservoir or reservoirs are mounted above and substantially parallel to the axis of the gun chamber.

I claim:

1. A mud gun having a clay feeding reservoir mounted thereon, said reservoir communicating with the chamber of the gun through a normally open connection, means for creating a discharging pressure on the clay in the reservoir, and piston means in the gun chamber effective for ejecting clay therefrom, the piston forming a closure for the open connection during a portion of the piston stroke.

2. A mud gun having a clay feeding reservoir mounted thereon and extending substantially parallel thereto, said reservoir communicating with the chamber of the gun through a normally open connection, means for creating a discharging pressure on the clay in the reservoir, and piston means in the gun chamber effective for ejecting clay therefrom, and for directly cooperating with said opening to control the feeding of clay from the reservoir to said chamber.

3. A mud gun comprising a gun chamber having a piston therein, a reservoir mounted on said gun chamber, and means for forcing clay from said reservoir into said gun chamber, there being an opening between said reservoir and gun chamber, the piston forming a closure for the opening during a portion of the piston stroke.

4. A mud gun, comprising a gun chamber, a piston movably mounted therein, a reservoir on said gun chamber and communicating therewith adjacent the limit of forward travel of the piston therein, and means operative for forcing clay from said reservoir into said gun chamber.

5. A mud gun, comprising a gun chamber, a piston movably mounted therein, a reservoir on said gun chamber and communicating therewith adjacent the limit of forward travel of the piston therein, and means operative for forcing clay from said reservoir into said gun chamber, said means comprising a fluid pressure cylinder and piston controlled thereby.

6. A mud gun, comprising a gun chamber, a piston movably mounted therein, a reservoir on said gun chamber and communicating therewith adjacent the limit of forward travel of the piston therein, and means operative for forcing clay from said reservoir into said gun chamber, said reservoir and said gun chamber having their axes substantially parallel.

7. In a mud gun, a gun chamber having an opening adjacent the forward end thereof for the admission of clay, means normally tending to force clay through said opening, and a piston in said gun chamber for ejecting clay from said chamber, said piston being directly effective for closing said opening at the limit of its forward stroke in said gun chamber.

8. In a mud gun, a gun chamber having an opening adjacent the forward end thereof for the admission of clay, means normally tending to force clay through said opening, and a piston in said gun chamber for ejecting clay from said chamber, said piston being directly effective for closing said opening at the limit of its forward stroke in said gun chamber, said means comprising a reservoir mounted on the gun chamber.

9. In a mud gun, a gun chamber having an opening adjacent the forward end thereof

for the admission of clay, means normally tending to force clay through said opening, and a piston in said gun chamber for ejecting clay from said chamber, said piston being directly effective for closing said opening at the limit of its forward stroke in said gun chamber, said means comprising a reservoir mounted on the gun chamber and having its axis substantially parallel to the axis 10 of the gun chamber.

10. In a mud gun, a gun chamber, a gun

piston, a reservoir for feeding clay into position within said chamber to be extruded by said piston, and means for operating said piston, said piston being directly effective 15 adjacent the limit of its ejecting stroke for sealing said gun chamber against the admission of clay thereto.

In testimony whereof I have hereunto set my hand.

EDGAR E. BROSIUS.
